SCREW COMPRESSOR

Carl Oscar Josef Montelius, Stockholm, Sweden,
assignor to Aktiebolaget Imo-Industri, Stockholm, Sweden, a company of Sweden

Application November 30, 1946, Serial No. 713,343

6 Claims. (Cl. 230—143)

1

This invention relates to screw compressors of the type having a plurality of intermeshing rotors enclosed in a housing and has particular reference to the securing of proper discharge from such a compressor.

In screw compressors the rotors are placed in a housing having inlet and outlet openings, the inside of the housing having intersecting bores to fit the outsides of the rotors. Contrary to the practice in the case of pumps for incompressible liquids, an end wall of the housing is located against the pressure (outlet) end of the rotors, to compress the volume enclosed in the individual grooves before the rotors have reached the rotary position where these grooves open to the outlet. Further it is a common practice to support the rotors by bearings to avoid contact between the rotors and the housing and to couple them by gear wheels to avoid direct friction between the screw threads of the intermeshing rotors. The shape of the screw threads is such that one of the cooperating rotors (the "male" rotor) is arranged with convex flange sides, the other (the "female" rotor) with concave flange sides (as in Patents 1,708,891 or 2,321,696) to avoid unnecessary leakage in all positions.

The outlet opening in the housing, which should be placed and dimensioned so that it permits a discharge at the right moment, when the compression in the grooves has reached a desired value, has been either placed sideways along the circumference of the rotors or in the pressure end wall or both ways. None of these arrangements, however, is satisfactory.

If the outlet is placed only sideways, it will allow the main part of the compressed gas to escape, but a small volume will be entrapped between the rotor threads and the end wall.

If, on the other hand, the outlet is placed in the end wall or so that it opens both sideways and to the end wall, this entrapped volume can escape, but then a direct passage from the outlet or high pressure side to the low pressure side cannot be avoided in certain positions of the rotors.

In the present invention a free outlet is arranged only sideways, the end of one of the co-operating rotors being closed by a valve plate fixed on this rotor with a necessary clearance with the end wall. In this valve plate passages from each rotor groove are made adjacent to one side of the rotor threads and cooperate with a channel in the end wall, which is connected to the outlet but covered by the valve plate. This channel is placed in such position that it drains the trapped volume to the outlet.

2

In the drawings,

Fig. 1 shows a length-wise section of a compressor according to the invention;

Fig. 2 is an end side view of the same compressor;

Figs. 3, 4 and 5 show a section along the line III—III in Fig. 1 illustrating the rotors in three different positions; and

Fig. 6 corresponds to Fig. 3, but involves a valve plate fixed upon the male screw instead of the female screw.

In Fig. 1 and Fig. 2 the housing is divided in two parts 1 and 2 secured together by four bolts and nuts indicated at 3. The ends of the housing are closed by two end covers 4 and 5. In the housing two rotors 6 and 7 are supported at one end by roller bearings 8 and at the other end by ball bearings 9. The rotor 6 has a driving shaft 10 to be driven by a motor. At the opposite end gear wheels 11 and 12 are fixed upon the rotor shafts, coupling them together. The inside of the two parts 1 and 2 of the housing is machined in the shape of two intersecting bores fitting the cylindrical outside surfaces of the rotors and the end walls of these bores are machined to planes fitting the plane ends of the rotors. The rotors are machined to screw shapes of opposite pitch, the rotor 6 being a male screw with convex flanges, the rotor 7 a female screw with concave flanges. The housing is further provided with an inlet opening 13 at one side and an outlet opening 14 at the other side. In Fig. 1 the inlet 13 and the outlet 14 are indicated by dotted lines.

At the outlet end of the rotor 7 a plate 15 is fixed upon the rotor. This end plate 15 and the rotors are further illustrated in Figs. 3, 4 and 5. The female screw 7 is designed with four threads 16 and is rotated in the direction indicated by the arrow. Along the back side 17 of each thread an oblong opening 18 is cut in the end plate. Along the end wall of the inside of the housing facing the plate a groove or channel 19 is machined forming a conduit for the compressed gas to the outlet 14.

In the operation of the machine the rotor 6 is rotated, driven by the shaft 10 and driving the rotor 7 by the gear wheels 11 and 12. The rotor threads have such a shape that the grooves on both rotors are closed by the threads of the other rotor and by the housing, making a set of closures, which are constantly moving lengthwise from the suction end wall 20 in Fig. 1 to the pressure end wall 21. These closures are filled by a fluid through the inlet 13 which is compressed during the rotation. In a certain

position the tops of the threads by their rotation reach a position where the closures open to the outlet opening 14. During the following rotation the main part of the volume in the closure is expelled through this outlet 14.

In Figures 3-5 the rotor ends close to the pressure end wall 21 are illustrated. The rotor groove 22 in the rotor 6 in Fig. 1 is marked by the same number in Fig. 3. This rotor groove opens to groove 23 in the rotor 7 in both Figs. 1 and 3. They form together a closure, which is in this position open to the outlet 14. The following grooves 24 in rotor 6 and 25 in rotor 7 form together another closure with a greater volume. This latter closure is open neither to the inlet, nor to the outlet and its volume will be compressed. The main part of the gas in these rotor closures, for instance 22 and 23, will escape to the outlet 14, but in each case a small part of the gas is trapped in the space 26, when the front face 27 of a flange of the male rotor 6 closes a groove 28 of the female rotor. This trapped volume escapes through the valve opening 18 to the channel 19 in the housing, which opens to the outlet 14.

During the following rotation the position shown in Fig. 4 is reached. The opening 18 is still open to the channel 19, but when the rotors have reached the position in Fig. 5, the opening 18 is shut off from the channel 19.

It is necessary that the opening 18 is placed only along the back side of the female rotor threads. Otherwise a passage would be created from the outlet 14 and the groove 19 to the back side 29, Fig. 4 and Fig. 5, of the male thread. The crescent-shaped area between the back side 29 and the female front side 30 indicates the beginning of a canal along the rotor threads, widening to the suction side or inlet. If therefore the opening 18 would be too wide and open to this crescent-shaped passage, the compressed fluid would escape this way causing a considerable loss and noise.

The valve plate can be fixed upon the male rotor instead of the female one. In Fig. 6 the arrangement of the passages is illustrated in a position corresponding to that of Fig. 3. The arrangement differs only from that previously described in that the openings 31 in Fig. 6 are placed along the front side 32 of the male screw instead of along the back side of the female screw as was previously described.

Of course, it is also possible to let the male rotor cooperate with two or more female rotors. Each of these female rotors should then be provided with a valve plate according to the invention. It is also possible, when a plurality of female rotors are used, to arrange a single valve plate upon the male rotor.

Having now particularly described the nature of my invention and the manner of its operation what I claim is:

1. A screw compressor including a housing, intermeshing male and female screw rotors within the housing, said housing having inlet and outlet openings, the outlet opening being laterally related to said screws to provide escape for elastic fluid compressed within the rotor grooves, and a valve plate carried by one of said rotors at the compression end thereof, said valve plate having a plane face engaging flatwise a plane surface on an end wall of the housing, said end wall of the housing having a passage therein providing communication between the region inside the part of the end wall which is within the circum-

ferences of both screws and said outlet opening, and said plate being provided with openings furnishing communication between the rotor grooves and said passage for the escape of elastic fluid entrapped in said grooves after closure of the grooves following their communication with the outlet opening.

2. A screw compressor including a housing, intermeshing male and female screw rotors within the housing, said housing having inlet and outlet openings, the outlet opening being laterally related to said screws to provide escape for elastic fluid compressed within the rotor grooves, and a valve plate carried by the male rotor at the compression end thereof, said valve plate having a plane face engaging flatwise a plane surface on an end wall of the housing, said end wall of the housing having a passage therein providing communication between the region inside the part of the end wall which is within the circumferences of both screws and said outlet opening, and said plate being provided with openings furnishing communication between the rotor grooves and said passage for the escape of elastic fluid entrapped in said grooves after closure of the grooves following their communication with the outlet opening.

3. A screw compressor including a housing, intermeshing male and female screw rotors within the housing, said housing having inlet and outlet openings, the outlet opening being laterally related to said screws to provide escape for elastic fluid compressed within the rotor grooves, and a valve plate carried by the female rotor at the compression end thereof, said valve plate having a plane face engaging flatwise a plane surface on an end wall of the housing, said end wall of the housing having a passage therein providing communication between the region inside the part of the end wall which is within the circumferences of both screws and said outlet opening, and said plate being provided with openings furnishing communication between the rotor grooves and said passage for the escape of elastic fluid entrapped in said grooves after closure of the grooves following their communication with the outlet opening.

4. A screw compressor including a housing, intermeshing male and female screw rotors within the housing, said housing having inlet and outlet openings, the outlet opening being laterally related to said screws to provide escape for elastic fluid compressed within the rotor grooves, and a valve plate carried by one of said rotors at the compression end thereof, said valve plate having a plane face engaging flatwise a plane surface on an end wall of the housing, said end wall of the housing having a passage therein providing communication between the region inside the part of the end wall which is within the circumferences of both screws and said outlet opening, and said plate being provided with openings furnishing communication between the rotor grooves and said passage for the escape of elastic fluid entrapped in said grooves after closure of the grooves following their communication with the outlet opening, each opening in said valve plate being adjacent to a side of a thread of the rotor which carries the plate.

5. A screw compressor including a housing, intermeshing male and female screw rotors within the housing, said housing having inlet and outlet openings, the outlet opening being laterally related to said screws to provide escape for elastic fluid compressed within the rotor grooves, and

a valve plate carried by the male rotor at the compression end thereof, said valve plate having a plane face engaging flatwise a plane surface on an end wall of the housing, said end wall of the housing having a passage therein providing communication between the region inside the part of the end wall which is within the circumferences of both screws and said outlet opening, and said plate being provided with openings furnishing communication between the rotor grooves and said passage for the escape of elastic fluid entrapped in said grooves after closure of the grooves following their communication with the outlet opening, each opening in said valve plate being adjacent to the leading side of a thread of said male rotor.

6. A screw compressor including a housing, intermeshing male and female screw rotors within the housing, said housing having inlet and outlet openings, the outlet opening being laterally related to said screws to provide escape for elastic fluid compressed within the rotor grooves, and a valve plate carried by the female rotor at the compression end thereof, said valve plate having a plane face engaging flatwise a plane surface on an end wall of the housing, said end wall of the housing having a passage therein providing communication between the region inside the

part of the end wall which is within the circumferences of both screws and said outlet opening, and said plate being provided with openings furnishing communication between the rotor grooves and said passage for the escape of elastic fluid entrapped in said grooves after closure of the grooves following their communication with the outlet opening, each opening in said valve plate being adjacent to the trailing side of a thread of said female rotor.
